CLAIM

The ornamental design for an extraction cleaner accessory tool, as shown and described.

DESCRIPTION

FIG. 1 is a front perspective view of an extraction cleaner accessory tool which embodies our design;

FIG. 2 is a front view thereof;

FIG. 3 is a rear view thereof;

FIG. 4 is a left side view thereof, the right side being a mirror image;

FIG. 5 is a top view thereof; and,

FIG. 6 is a bottom view.

Portions of the extraction cleaner accessory tool shown in broken lines form no part of the claimed design.
